(57) CLAIM

The ornamental design for a flower brush, as shown and described.

DESCRIPTION

FIG. 1 is a front view of a flower brush showing my new design;

FIG. 2 is a right side view thereof;

FIG. 3 is a front view of the flower brush shown without the base for completeness of illustration;

FIG. 4 is a left side view of FIG. 3;

FIG. 5 is a rear view of FIG. 3; and,

FIG. 6 is a front view of the flower brush base of FIG. 1 shown separately for completeness of illustration 1.

The broken lines shown in all FIGS. 1-5 are for environmental purposes and from no part of the claim.
